NEEDLE MOTION FOR AXMINSTER LOOMS

Application filed July 5, 1928. Serial No. 290,330.

This invention relates to needle motions for Axminster looms and it is the general object of the invention to provide a continuously moving power arm with such connections to the needle as will give the latter dwells of unequal lengths such as are necessary in the ordinary operation of an Axminster loom.

In wide Axminster looms the weft laying needle is usually operated by a flexible cable secured to a drum which is caused to oscillate in opposite directions by a segmental gear. The segment is ordinarily operated by a connector extending from a crank arm which is moved intermittently by a large mutilated bevel gear. The intermittent operation due to the mutilated gear is used to secure the dwells of unequal length which are necessary in the operation of the loom. It is to be understood that when the needle is in the shed and cooperating with the selvage shuttle it is necessary that the needle have only a slight dwell of sufficient length to permit the passage of the shuttle, but when the needle is out of the shed and the lay is moved forwardly to beat in the double pick it is necessary that the motion have a longer dwell. Because of the intermittent motion heretofore used the parts are subjected to a rather harsh and sudden operation which is found in some instances to interfere with increasing the speed at which the loom is operated.

It is accordingly an important object of my present invention to provide a continuously moving member which is coupled to the segment gear by a mechanical device which causes the needle to be given its proper long and short dwells and thus permit the loom to be run at an increased speed over that which has been found feasible heretofore.

It is an important object of my invention to couple with the usual constantly rotating crank arm a toggle which in one extreme position adds its dwell to that of the crank arm but which in the other extreme position adds

practically nothing to the dwell of the crank, so that in one position the needle is given a short dwell and in the other position it is given a longer dwell.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of a portion of a needle motion made according to my present invention, showing the parts in the position they assume when the needle is entirely in the shed,

Fig. 2 is a diagrammatic view illustrating the relation of the parts when they are in the position shown in Fig. 1 and it is necessary to produce a slight dwell only in the motion of the needle, and

Fig. 3 is another diagrammatic view but showing the relation of the parts in the position they assume when the needle is out of the shed and it is necessary to produce a longer dwell in the motion of the needle.

Referring to Fig. 1, I have shown a loom frame 10 from the right hand end of which extends a needle motion frame 11. The latter supports a needle rail 12 which guides and supports the needle carriage 13. The needle 14 is secured to the carriage and has an eye 15 through which the weft W extends.

On that side of the loom opposite the needle motion there is located a selvage forming mechanism including an upright shaft 16 oscillated about its axis by mechanism not shown to cause reciprocating movements of a head 17. A fixed shuttle race 18 receives a shuttle S, and the parts are so timed that when the needle is in the position shown in Fig. 1 the shaft 16 will be given an oscillation to move the shuttle across the vertical plane in which the needle 14 lies, the shuttle being

caused by the head to pass through recess 19 in the needle and therefore through the loop formed in the weft W to interweave the selvage warp with the filling. This part of the 5 mechanism is very well understood and its operation is believed to be apparent without further description.

The needle carriage 13 is caused to reciprocate back and forth along the rail 12 by means 10 of a flexible cable 20 the left hand end of which is guided by a sheave 21 rotatable about a fixed axis 22 and the right hand end of which is guided by a movable sheave 23 supported on a stud 24. The latter is carried by an arm 15 25 formed as part of a take-up lever 26 pivoted as at 27 to an upstanding horn 28 supported by the needle rail 12. The lever 26 may be provided with a segment 29 to co-operate with a holding pawl 30 pivoted to the 20 frame. A weight 31 acts to move the lever 26 about the axis 27 in a counter-clockwise direction, tending always to move the sheave 23 to the right as viewed in Fig. 1 for the purpose of keeping the cable 20 taut.

25 The cable is secured to a drum 32 secured to a rock shaft 33 having keyed thereto a driving pinion 34. Said pinion meshes with a segmental gear 35 which swings about a fixed stud 36 as an axis. A shaft 37 is given 30 a constant rotation by means not shown but well understood and operates by mechanism to be described hereinafter to drive a shaft 38 to which is secured a crank arm 39.

The matter thus far described is common 35 construction in wide Axminster looms and with the exception of the character of motion to be imparted to the crank arm 39 forms no part of my present invention.

In carrying my present improvements into 40 effect I provide for giving the crank arm 39 a continuous rotary movement and for connecting the same to a toggle which operates when in one extreme position to add its retarding effect to that of the crank arm, but which acts 45 when in the other extreme position to permit the retarding to be due almost exclusively to that derived from the crank arm. Accordingly, I provide a continuously rotating bevel gear 50 which meshes with the bevel pinion 51 secured to the shaft 38. In this way continuous and preferably uniform rotation is communicated from the driving shaft 37 to the shaft 38 to cause the arm 39 to rotate with a continuous and preferably uniform movement.

55 The toggle to which reference has been made is formed of two links, the segment link 52 being connected to the segment by a stud 53 which is adjustable in slot 54 in a direction 60 toward and from the stud 36 or axis of the segment. The anchored link 55 moves about a fixed pivot 56 which may be supported by the frame 11 and is connected to the segmental link by means of a stud 57. A connector 58 is 65 pivotally attached to the arm 39 by means of

a stud 59 and is pivoted to the stud 57 as shown in Fig. 1.

Referring more particularly to the diagrammatic Figs. 2 and 3 I have shown how I obtain the dwells of two different degrees from the continuously moving arm 39 and the toggle. In Fig. 2 there is illustrated the means by which the shorter dwell is provided when the needle is in the shed and cooperating with the selvage shuttle. In Fig. 2 the parts 70 are shown in full lines in substantially the position they occupy in Fig. 1. As the crank arm 39 rotates in the direction indicated by arrow A it will assume the position shown in dotted lines at B. When the arm 39 is so located as to be in the position suggested by position B the stud 57 will be not quite at its lowest position and the right hand end of the segment will be in the position indicated at the dotted lines C.

85 As the crank arm continues to rotate its pivotal connection with the link 58 will pass through the line joining the center of the shaft 38 and the stud 57, in which position the latter will be in its lowest position so that the segment gear 35 will move to its extreme left hand position and assume the full line position shown in Fig. 2. As the crank arm continues to move it will assume a position shown at the dotted line D in Fig. 2, causing the segment to move back to the dotted line C. It will be seen, therefore, that a considerable angular movement takes place on the part of the crank arm 39 with a very slight corresponding movement on the part of the segment 90 35.

95 As the crank arm continues to move in the direction of arrow A it will act to move the needle out of the shed and it is while the needle is out of the shed and the lay is beating up that it is necessary to provide the longer dwell. As shown in Fig. 3 the crank arm will in the course of its revolution around shaft 38 assume the position E, the links 52 and 55 during that part of the revolution preceding the arrival of the crank arm at the position E having moved to increase the angle between them and therefore cause the segment to move to the right as viewed in Fig. 3.

100 With the crank arm in the position E in Fig. 3 the point of connection between the toggle links and the connector will be at the position shown at F and as the crank arm continues to rotate it will cross the line extending from stud 57 and projecting through 105 the center of the shaft 38, in which position the toggle links will be practically aligned and the toggle therefore straightened out to give its maximum effect to move the segment 35 to the full line position shown in Fig. 3. 110 When the crank arm is in the position indicated at E the right hand end of the segment will assume the position indicated at G in Fig. 3 and by reference to Fig. 2 it will be 115 seen that the space between the final posi- 120 125

tion of the segment to the left and line C is practically the same as the distance between line G and the final position to the right of the segment, but it will be noted that the angular distance the crank arm moves from position E to the full line position in Fig. 3 is considerably greater than is the angular movement of the crank arm from position B to the full line position in Fig. 2. This is due to the fact that the natural retarding of the movement due to the straightening of the toggle joint is added to the retarding of the crank arm and these two retardations, being simultaneous, give the necessarily long dwell with the needle out of the shed. As the crank continues to move from the straight line position to position H in Fig. 3 the segment 35 will move back to the dotted line G.

It is to be understood that the parts are so proportioned that the retardation will not become appreciable until the needle is practically out of the shed, so that there need be no delay in the beating up of the lay due to too gradual a slowing down of the motion of the needle.

From the foregoing it will be seen that I have provided a simple but rugged needle motion so designed that when the crank arm is in one position a slight dwell is produced in the motion of the needle, the toggle being ineffective to cause a dwell at that time, but that when the arm is substantially in the opposite position a considerably increased dwell is produced due to the additional dwell brought about by straightening the toggle. The increased dwell thus derived is of such duration as to permit the needle to be driven by a continuously and preferably constantly moving source of power. It will further be seen that I interpose between the segment and the shaft 38 two mechanical devices one of which by the nature of its motion causes two dwells in its cycle of operation and the other of which causes but one dwell in its cycle of operation, and that I so relate these parts that when in one extreme position only one device is effective to make its dwell felt in the motion of a needle, but that when in the other extreme position both devices act jointly to produce a dwell of increased length.

Having thus described my invention it will be seen that changes and modifications may be made therein by those skilled in the art without departing from the spirit and scope of the invention and I do not wish to be limited to the details herein disclosed, but what I claim is:

1. In a needle motion for an Axminster loom, a continuously moving driving member, a weft laying needle movable into and out of the shed of the loom, a driven oscillating member to be oscillated at different rates of speed and operatively connected to the needle, two connected mechanical devices, one for each member, each device being mov-

able to two extreme positions, one of said devices being effective to cause a retardation on the part of the oscillating member when the needle is in the shed and also out of the shed, and the other device being effective to cause a retardation in the movement of the oscillating member when the needle is out of the shed.

2. In a needle motion for an Axminster loom, a continuously moving driving member, a weft laying needle movable into and out of the shed of the loom, a driven oscillating member to be oscillated at different rates of speed and operatively connected to the needle, two connected mechanical devices, one of said devices being operatively connected to the driving member and the other device being operatively connected to the oscillating member, each of said devices being movable through two extreme positions, the device operatively connected to the driving member being effective to cause a retardation in the motion of the oscillating member when the needle is in the shed and also out of the shed, and the other device operatively connected to the oscillating member being effective to cause a retardation in the movement of the latter when the needle is out of the shed.

3. In a needle motion for an Axminster loom, a continuously moving driving member, a driven oscillating member to be oscillated at different rates of speed, a needle movable into and out of the shed of the loom and operatively connected to the oscillating member, a pair of mechanical devices operatively connected together, one device being connected to one member and the other device being connected to the other member, said devices simultaneously passing through two extreme positions, one of said devices effective to cause a retardation in the movement of the oscillating member when the needle is in and also out of the shed and the other device being effective to retard the movement of the oscillating member when the needle is out of the shed.

4. In a needle motion for an Axminster loom, a continuously moving driving member, a driven oscillating member to be oscillated at different rates of speed, a needle movable into and out of the shed of the loom and operatively connected to the oscillating member, two mechanical devices interposed between the members, one of said devices effective to produce two retardations for each cycle of movement of the oscillating member, one retardation when the needle is in the shed and the other when the needle is out of the shed, and the other device being effective to produce one retardation only in the cycle of movement of the oscillating member when the needle is out of the shed.

5. In a needle motion for an Axminster loom, a continuously moving driving member, a driven oscillating member to be oscil-

lated at different rates of speed, a needle movable into and out of the shed of the loom and operatively connected to the oscillating member, two mechanical devices interposed between the members, one of said devices effective to produce two retardations for each cycle of movement of the oscillating member, one retardation when the needle is in the shed and the other when the needle is out of the shed, and the other device being effective to produce one retardation only in the cycle of movement of the oscillating member when the needle is out of the shed, two of the retardations of the devices occurring simultaneously.

6. In a needle motion for an Axminster loom, a continuously moving driving member, a driven oscillating member to be oscillated at different rates of speed, a needle movable into and out of the shed of the loom and operatively connected to the oscillating member, a pair of mechanical devices interposed between the members, each device receiving a complete movement for each complete oscillation back and forth of the oscillating member, one of said devices effective to produce a retardation at two spaced points in the operation of the oscillating member, one retardation when the needle is in the shed and the other when the needle is out of the shed, and the other device effective to produce but one retardation in the movement of the oscillating member when the needle is out of the shed.

35 7. In a needle motion for an Axminster loom, a continuously moving driving member, a driven oscillating member to be oscillated at different rates of speed, a needle movable into and out of the shed of the loom and operatively connected to the oscillating member, a pair of mechanical devices interposed between the members, each device receiving a complete movement for each complete oscillation back and forth of the oscillating member, one of said devices effective to produce a retardation at two spaced points in the operation of the oscillating member, one retardation when the needle is in the shed and the other when the needle is out of the shed, and the other device effective to produce but one retardation in the movement of the oscillating member when the needle is out of the shed, two of the said points of retardation caused by the devices being simultaneous.

8. In a needle motion for an Axminster loom, a continuously moving driving member, a driven oscillating member to be oscillated at different rates of speed, a needle movable into and out of the shed of the loom and operatively connected to the oscillating member, two mechanical devices interposed between the members and operatively connected together to be movable simultaneously through two extreme positions, both of said

devices effective to produce a retardation in the movement of the oscillating member when the needle is out of the shed and only one of said devices being effective to produce a retardation in the movement of the oscillating member when the needle is in the shed.

9. In a needle motion for an Axminster loom, a continuously moving driving member, a driven oscillating member to be oscillated at different rates of speed, a needle movable into and out of the shed of the loom and operatively connected to the oscillating member, a crank operatively connected to one member, a toggle operatively connected to the other member, means to connect the crank and toggle together to transmit motion from the driven member to the oscillating member, said crank effective to produce two retardations in the motion of the oscillating member for each complete revolution of the crank, one retardation when the needle is in the shed and the other when the needle is out of the shed, and the toggle being effective to produce but one retardation for each complete revolution of the crank when the needle is out of the shed.

10. In a needle motion for an Axminster loom, a continuously moving driving member, a driven oscillating member to be oscillated at different rates of speed, a needle movable into and out of the shed of the loom and operatively connected to the oscillating member, a crank operatively connected to one member, a toggle operatively connected to the other member, means to connect the crank and toggle together to transmit motion from the driven member to the oscillating member, said crank effective to produce two retardations in the motion of the oscillating member for each complete revolution of the crank, one retardation when the needle is in the shed and the other when the needle is out of the shed, and the toggle being effective to produce but one retardation for each complete revolution of the crank, the retardations of the crank and toggle being added to cause the retardations in the motion of the oscillating member to be of unequal durations.

11. In a needle motion for an Axminster loom, a continuously moving driving member, a driven oscillating member to be oscillated at different rates of speed, a needle movable into and out of the shed of the loom and operatively connected to the oscillating member, a crank connected to the driving member, a toggle connected to the oscillating member, means connecting said crank and toggle together, said crank effective in a complete revolution thereof to cause two retardations in the movement of the oscillating member, one retardation when the needle is in the shed and the other when the needle is out of the shed, and said toggle effective during a complete revolution of the crank to produce but one retardation in the movement of the

oscillating member when the needle is out of the shed.

12. In a needle motion for an Axminster loom, a continuously moving driving member, a driven oscillating member to be oscillated at different rates of speed, a needle movable into and out of the shed of the loom and operatively connected to the oscillating member, a crank connected to the driving member, a toggle connected to the oscillating member, means connecting said crank and toggle together, said crank effective in a complete revolution thereof to cause two retardations in the movement of the oscillating member, one retardation when the needle is in the shed and the other when the needle is out of the shed, and said toggle effective during a complete revolution of the crank to produce but one retardation in the movement of the oscillating member, when the needle is out of the shed the retardations due to the toggle being added to and simultaneous with one of the retardations caused by the crank.

13. In a needle motion for an Axminster loom, a continuously rotating crank arm, an oscillatable segment member, a needle movable into and out of the shed of the loom and operatively connected to the oscillating member, an anchored toggle link movable about a fixed axis, a segment toggle link pivotally connected to the segment member, means to connect said links and crank together, said crank when in one extreme position causing the links to be angularly disposed to effect a slight retardation in the movement of the segment member when the needle is in the shed, and said crank when in the other extreme position and when the needle is out of the shed being effective to move the links into substantial alignment to cause a retardation in the motion of the segment member greater than the first named retardation.

14. In a needle motion for an Axminster loom, a continuously moving crank arm, a needle movable into and out of the shed of the loom, an anchored toggle link movable about a fixed axis; an oscillatable segment operatively connected to the needle, a segment toggle link operatively connected to the segment, a connector pivotally connected to the crank arm, means pivotally connecting the anchored and segment links together with the connector, said crank when passing through a complete revolution being effective to cause two retardations in the movement of the segment member at different times in a revolution of the crank arm, one retardation when the needle is in the shed and the other when the needle is out of the shed, said crank arm and links being so proportioned that when the crank arm is in one position to effect one retardation in the motion of the segment member said toggle member will be angularly disposed and ineffective to cause

a retarding of the movement of the segment member and said crank when in the other position effective to cause substantial alignment of the toggle links, said substantial alignment causing additional retardation in the movement of the segment member when the needle is out of the shed. 70

In testimony whereof I have hereunto affixed my signature.
